UNITED STATES PATENT OFFICE.

CARL I. HAYES, OF PROVIDENCE, RHODE ISLAND.

ELECTRIC FURNACE.

Application filed May 12, 1928. Serial No. 277,931.

The present invention relates to a novel method and to an improved apparatus for the heat treating of metals and has for an object the providing of a heat-treating furnace having means for heating a work-receiving chamber to a high degree, and the projecting of a thin film of highly heated gases across the mouth or entrance of the furnace to form a transparent, colorless, protecting curtain through which the condition of the work in the chamber may be clearly observed during the heat treating process.

A further object of the invention is to provide a furnace for heat treating metals having a narrow opening thru which the gases are forced to form the transparent curtain across the entrance to the chamber, the curtain being capable of excluding the external air from the chamber and means being also provided for varying the character or proportions of the curtain forming gases to affect the atmospheric condition in the chamber and the action of the heat in the chamber upon the work therein.

The invention further consists in the provision of electrical means for heating the work-receiving chamber and independent means for forming a thin film or curtain of gases across the entrance of the work-receiving chamber.

The invention may be carried out in various ways, but for the purpose of the present disclosure one example of an apparatus is shown in the accompanying drawings, in which:

Fig. 1 is a front view of the electrically heated furnace showing one means by which gases may be introduced to form a thin film or curtain across the entrance to the furnace chamber.

Fig. 2 is a central sectional view on line 2-2 of Fig. 1 showing one arrangement of electrical heating units and showing a slit or slot in the lower wall of the chamber thru which curtain forming gases may be introduced.

Fig. 3 is a section on line 3-3 of Fig. 2 showing one arrangement of electrical heating units and a slot in the lower wall of the chamber for introducing a thin film of gases to form a curtain across the mouth of the work-receiving chamber.

Fig. 4 is a diagrammatic view illustrating one arrangement of a group of heating units electrically connected together.

With reference to the drawings the inven-

tion may be practiced by providing a furnace 10 built of suitable refractory material within which is formed a work-receiving chamber 12 which may be heated either by gas or electricity in any suitable way; that herein shown being arranged to be heated by an electric current passing thru a group of resistance bars 13, in which group the circuit wires are connected to the terminal rods 14 and the current is controlled by a switch 15 by which construction the chamber 12 may be heated to a high degree for hardening, tempering, annealing or to any desired degree for otherwise treating metals by the application of heat thereto, and the furnace is herein shown as being supported on the legs 11. It is preferred to use an electric heater for the furnace chamber 12 because the heat can be better regulated and will better maintain constant temperatures.

The essential feature of my present invention is the provision of means for introducing a film of gases to form a transparent curtain across the mouth or entrance of the furnace chamber and which will seal or exclude atmospheric air from the chamber 12 and will fill the chamber so as to produce the most suitable atmospheric condition therein. One means of accomplishing this result is to form a narrow slot or opening 16 in the lower wall 17 of this chamber, the slot extending across the throat of the chamber from side to side thereof, to provide a relatively long discharge jet or nozzle. This slot is connected to a tube or pipe 18 providing a gas combustion chamber to which is attached a gas feeding pipe 19 and an air introducing pipe 20 leading from the blower 26, the openings in these pipes being controlled and varied to suit the conditions under which the furnace is operating.

When this mixture of air and gas is introduced thru these pipes 19 and 20 to mix in the larger combustion tube or chamber 18, this mixture is ignited thru the vent hole 22 in the pipe 18. The products of combustion from the gas thus ignited are forced by the pressure of the gas and the air into this slot or jet 16.

These products then spread throughout the length of the slot and are forced upwardly to form a thin film or curtain 23 across the mouth or opening 24 of the chamber 12, the pressure of these curtain gases serving to exclude the outside air from the

work receiving chamber; also a portion of these gases when striking the opposite wall of the entrance opening flow into the chamber 12 and fill the same. The oxygen which 5 is first found in the chamber mixes with the curtain gases and is dissipated so that the proper atmospheric condition within the chamber is obtained to prevent the work subsequently introduced from oxidizing 10 while being subjected to the heat in the chamber.

It is found in practice by varying the proportions of the air and gas used to form this curtain by the valves 21 and 25, respectively, that the proper or desired atmospheric conditions within the furnace may also be regulated and maintained so as to obtain different desired effects upon the work being treated. Also it is found that these 20 atmospheric conditions within the furnace may be varied without appreciably affecting the temperature of the chamber.

My improved furnace is very practical in its operation and by its use the condition of 25 the work within the furnace chamber may be observed and the desired atmospheric conditions therein maintained during the heat treating operation.

The foregoing description is of an apparatus shown to illustrate one manner in which the invention may be practiced, but I desire it to be understood that I reserve the privilege of resorting to all the methods and mechanical devices by which the invention may 35 be performed, the invention being defined and limited only by the terms of the appended claims.

I claim:

1. In a furnace for treating metals, a heating chamber having an opening therein through which the materials to be treated are inserted in and removed from said chamber, said chamber being otherwise closed, and means for projecting an unbroken stream of 40

45 combusted gases under pressure across said opening to form a transparent, colorless curtain for totally excluding outside atmospheric air from the chamber.

2. In a furnace for treating metals, a heating chamber having an opening therein and through which the materials to be treated are inserted in and removed from said chamber, said chamber being otherwise closed, 50 sources of gas supply, a gas combustion chamber connected with said sources of gas supply, and means for directing products of combustion from said combustion chamber in an unbroken stream across said opening to form a transparent, colorless curtain totally 55 excluding outside atmospheric air from the chamber.

3. A device for controlling the atmospheric condition within a heating chamber having a door opening therein, comprising a combustion chamber, means for supplying regu- 60

lated quantities of combustible and oxygen bearing gases thereto, and means for delivering combusted gases from said combustion chamber in an unbroken curtain across the door opening to exclude outside atmospheric air from said heating chamber. 70

4. A device for controlling the atmospheric condition within a heating chamber having a door opening therein, comprising a combustion chamber, means for supplying regulated quantities of combustible and oxygen bearing gases thereto to produce combusted gases of predetermined constituency, and means for delivering the combusted 75 gases from said combustion chamber in an unbroken curtain across and within said door opening to exclude outside atmospheric air from said heating chamber and to fill said heating chamber with combusted gases. 80

5. A device for controlling the atmospheric condition within a heating chamber having a door opening therein, including a combustion chamber, means for supplying combustible and oxygen bearing gases thereto, means for delivering combusted gases 85 from said combustion chamber in an unbroken curtain across and within the door opening to exclude outside atmospheric air from the heating chamber and to fill said heating chamber, and means for controlling the relative proportions of the gases supplied to the combustion chamber so that the constituents 90 of the curtain forming gases will produce suitable atmospheric conditions within the chamber. 95

6. In a furnace for heating metals, a heating chamber having a door opening therein and otherwise closed, a nozzle slot positioned parallel to and adjacent one side of the opening, and means to supply said nozzle slot with combusted gases under pressure to project an unbroken sheet of gases across said door opening from said nozzle slot for excluding 100 atmospheric air from said chamber. 105

7. In a furnace for heating metals, a heating chamber having a door opening therein, and otherwise closed, a throat adjacent said door opening, a nozzle slot positioned within said throat parallel to and adjacent one side of the opening and comprising two longitudinally extending closely adjacent walls, and means to supply said nozzle slot with transparent, colorless, combusted gases of predetermined composition and under pressure, whereby an unbroken thin smooth sheet 110 of said gases is projected across said door opening during heat treatment to impact on the opposite wall of the chamber. 115

8. In an electric furnace for treating metals, a heating chamber having an opening therein through which the materials to be treated are inserted in and removed from said chamber, said chamber being otherwise closed, electrical means for heating said chamber, and means for projecting an un- 120 125 130

broken stream of combusted gases under pressure across said opening to form a transparent, colorless curtain for totally excluding outside atmospheric air from the chamber.

- 5 9. In an electric furnace for heating metals, a heating chamber having a door opening therein and otherwise closed, electrical means for heating said chamber, a nozzle slot positioned parallel to and adjacent one 10 side of the opening, and means to supply said nozzle slot with combusted gases under pressure to project an unbroken sheet of gases across said door opening from said nozzle slot for excluding atmospheric air from said

metals, a heating chamber having a door opening therein, electrical means for heating said chamber, and a device for controlling the atmospheric condition within said heating chamber comprising a combustion chamber, means for supplying regulated quantities of combustible and oxygen bearing gases thereto to produce combusted gases of predetermined constituency and means for delivering the combusted gases from said combustion chamber in an unbroken curtain across the door opening to exclude outside atmospheric air from said heating chamber. 20 25

In testimony whereof I affix my signature.

CARL I. HAYES.
